UNITED STATES PATENT OFFICE

MERRILL DAVIS, OF DETROIT, MICHIGAN

REFRIGERATING MACHINE

Application filed October 25, 1926. Serial No. 144,079.

My invention relates to the flooded system compression type of refrigerating machines and has for its object the provision of means whereby the refrigerant will be transferred 5 from the condenser or high side to the expansion or low side by mechanical means which are positive in their action and are unaffected by variations in pressure and temperature and will allow the entire charge 10 of refrigerant to be contained in the low side or freezing unit and thereby eliminate any possibility of flooding or overcharging the low side.

Another object is to provide means whereby 15 the gas that is formed in the low side may pass to the compressor in a path that is entirely separated from that portion of the crank case where the lubricating oil is agitated by the action of the crank, and 20 thereby prevent any of the oil from being entrained and carried with the gas through the valves and over into the condenser.

Another object is to provide a suction valve 25 of very liberal dimensions and simple design arranged so as to reduce the clearance space to the smallest possible amount.

Still another object is to provide a machine the component parts of which will permit the use of modern high production 30 machinery in their manufacture and are so arranged that the entire machine may be placed in or removed from the cabinet without breaking a line at any point.

With these and other objects in view the 35 invention consists in the construction as hereinafter set forth.

In the drawings:

Figure 1 is a vertical central section through my improved machine.

Figure 2 is a cross section taken at substantially right angles to Figure 1, certain parts being shown in elevation for the sake of clearness.

As shown A is a box or refrigerating chamber of any suitable construction. B is a re-

movable lid or cover for this box upon which the refrigerating unit is mounted and which permits of radially detaching said unit for service. The unit comprises a portion mounted above the cover B including the 50 compressor pump C, crank shaft D, pulley E and condenser coil F. Also beneath the cover and suspended therefrom is the expansion or refrigerating portion of the unit G which is connected with the apparatus above 55 the cover as hereinafter described.

As has been stated, the system which I employ is of the flooded type and to provide the necessary radiating surface and capacity for holding the liquid refrigerant as well as to 60 permit the removal of the gas therefrom I have devised the following construction. The combined container and radiator is formed of a series of sections each comprising the pressed sheet metal members H and H' spaced from each other and having the overlapping marginal flanges H² H³ sealed by brazing, soldering or any suitable way. These members H and H' are of an area determined by the capacity required and having 65 portions cut away as indicated at I for the reception of transversely extending ice freezing trays J also in the upper portion of each section which form circular apertures surrounded by oppositely extending annular flanges H⁴, H⁵. These surround an annular bushing K which has a series of apertures K' therethrough connecting the space without to the space within. The members H, H' also are preferably provided with a series of 70 inwardly extending portions H⁶ which bear against and are welded or otherwise fastened to the opposite member and form spacers and ties between said members.

The radiator G is formed of a series of the 85 sections just described which are united to each other by engaging the bushing rings K with spacer rings L thereby holding the sections suitably spaced from each other and in parallel relation. The whole series is 90

clamped by a bolt or tie rod L' which at one end has a threaded engagement with a casing M and at its other end with a hanger bracket M', gaskets L² being placed between the rings K and L. The casing M extends upward through the cover B and is attached to the portions above said cover as will be presently described.

- Compressor unit**
- 10 The cylinder of the pump C is integral with the crank casing C' and the crank shaft D is journaled in bearings D', D² which are a part of a secondary crank case Q³ which is positioned at one side of the crank casing.
- 15 Between the bearings D', D² is a worm D³ intermeshing with a worm gear D⁴ on a transverse eccentric shaft D⁵ the eccentric portion of which is shown at D⁶. Located at each
- 20 side of worm gear and on the eccentric portion of shaft are the vertically disposed links D' engaging at their lower end with a vertically disposed plunger N. This plunger passes through a packing gland N' into a chamber N² having a cylindrical well N³ in alignment with the plunger and laterally connected at N⁴ with the lower end of the condenser coil F. The well N³ has a bottom port N⁵ normally closed by the ball valve N⁶ under the compression of a spring N'. The arrangement is such that the plunger N in its reciprocation will alternately enter and be withdrawn from the well N³ while the condensate from the coil F will flow into the
- 25 chamber N² and drain into the well. Thus whenever sufficient liquid accumulates in the well the pressure of the plunger thereon will force open the valve N⁶ permitting this liquid to drain through the port N⁵ into communication with the space formed by the aligned bushings K. The level is so established that the refrigerant liquid will occupy a small portion of the space within said bushings while the greater portion of said space is
- 30 free to receive the gas generated by the evaporation or boiling of the liquid in the several radiator units.
- 35 The piston C² of the compressor which is connected by the rod C³ with the crank is reciprocated in the cylinder with very slight clearance. The inlet valve O is of annular form surrounding the piston and cylinder and controlling an annular series of inlet ports O' in the valve seat O². This seat extends into a recess in the cylinder head O³ and the clearance between the seat and said head is only sufficient to permit a movement of the valve O which will open the ports O'. The outlet valve P controls a central port P' in the head O³ and is arranged in a recess P² in the upper portion of said head. The valve P normally rests upon a seat P³ and is limited in its upward movement by a spider P⁴. This spider is however yieldably held in position
- 40 by a spring P⁵ so that in case any liquid

should accumulate in the pump the valve P will be permitted to open wider by compressing said spring. There is also arranged a plug P⁶ attached to the upper end of the piston and approximately filling the port P' so as to diminish the clearance to the minimum.

70 The inlet ports O' communicate with an annular recess Q beneath the seat O² and which is connected with a downwardly extending tubular passage Q' in the wall of the cylinder. The lower end of this passage communicates with the chamber Q² in a casing Q³ which chamber contains the worm gearing D³, D⁴ but is divided from the crank by a partition Q⁴. An aperture Q⁵ establishes communication between the chamber Q² and the crank chamber but this passage is located below the normal level of the lubricating oil so that the splashing of oil in the crank chamber by the crank will not materially disturb the oil in the chamber Q². R are passages extending downward through the casing M connecting at their lower ends with a port R' communicating with the chamber within the bushings K. The upper ends of the passages R are connected with tap bolts R² which serve to hold the caps R³ for the bearings of the shaft D⁵ and which are further provided with tubes R⁴ which extend upward to near the top of the chamber Q². Thus the construction is such that the vapor accumulating in the chamber formed by the bushings K will pass through the port R' into the passages R and upward therethrough and through the tubular extensions R⁴ into the chamber Q². From here the vapor is further conducted upward through the passage Q' into the annular passage Q and through the ports O' and past the valve O into the compression cylinder. During such passage the vapor is kept out of contact with the lubricating oil thereby avoiding danger of carrying the oil into the cylinder and the compression coil.

100 105 110 115 120 125 130

With the construction as described, the unit mounted on the cover B may be easily placed in connection with the ice box and as easily removed therefrom. The joint between the cover and the box may be sealed by a suitable pneumatic gasket S which will prevent the entrance of warm air. The motor (not shown) for driving the pulley E may, if desired, be mounted permanently on the ice box thereby reducing the weight of the removable unit.

In operation the expansion unit is filled with a liquid refrigerant up to the desired level and as vaporization takes place the vapor generated will pass through the ports K' into the space within the hollow bushings K. From here it is drawn upward into the pump through the passages previously described and after compression the gas is ejected through the ports K' into the upper

end of the expansion coil F. This coil is located in a suitable casing T having louver openings T' therein and the pulley E is provided with fan spokes E' for forcing air through the coils and out through the louver openings. As fast as condensation takes place in the coil E the liquid will drain into and accumulate in the chamber N² and well N³ from which it will be ejected by the reciprocation of the plunger N. However the tension of the spring N⁷ will normally hold the valve N⁶ closed so as to avoid escape of pressure from the high pressure side of the system into the low pressure side. By this arrangement practically all of the liquid refrigerant is held in the radiator unit G and all of the space on the high pressure side of the system is available for reception of the gas to be condensed. Some of the advantages of my construction are first that the radiator sections are inexpensive to manufacture and may be designed in form with respect to the space in which the unit is located. Furthermore the size of the unit may be varied by adding or removing sections so that any desired capacity may be obtained. Second, the forming of the inlet valve as an annulus surrounding the piston and controlling a series of ports in the annular valve seat permits of reducing the clearance to the minimum and at the same time providing abundant area for the passage of the gas through the valve. Third, the separation of the crank chamber in which splash lubricant occurs from the chamber containing the gears and the conducting of the gas to the upper portion of the latter chamber avoids carrying the lubricant oil into the system. Fourth, the plunger N which positively ejects the accumulated condensate from the high pressure side of the system into the low pressure side frees the condenser oil from condensate without permitting escape of pressure.

4. What I claim as my invention is:

1. In a refrigerating apparatus the combination with a compressor and expansion and compression chambers adjacent thereto, of means for positively ejecting condensate from the pressure side of the system into the expansion side thereof.

2. In a refrigerating apparatus the combination with a compressor pump and compression and expansion chambers adjacent thereto and respectively at upper and lower levels, of means for positively ejecting condensate accumulated in the lower portion of said compression chamber into said expansion chamber.

3. In a refrigerating apparatus the combination with a compressor pump and compression and expansion chambers adjacent thereto, of a crank shaft for operating said pump, a step down gearing operated by said crank shaft and an ejector plunger actuated

by said gearing for positively displacing condensate accumulated in the pressure side of the system into the expansion side thereof.

4. In a refrigerating apparatus, the combination with a compressor pump and expansion and compression chambers adjacent thereto, of a crank shaft for operating said pump and a chamber enclosing said crank shaft and depending therefrom being provided at its lower end with a chamber for the reception of condensate from the compression chamber, a spring closed valve controlling the port connecting said chamber with the expansion side of the system, a step down gearing on said crank shaft and a plunger actuated by said step down gearing for displacing condensate in said chamber against the pressure of said spring closed valve.

5. In a refrigerating unit, the combination with a refrigerator casing and a removable cover therefor, of a refrigerating unit comprising a compressor and condenser mounted on the top of said removable lid, an expansion unit secured to and depending from said cover and compressor a crank shaft for operating said compressor, step down gearing on said crank shaft, a plunger actuated by said step down gearing having its lower end engageable with a recess in said casing for receiving condensate from said condenser and a spring closed valve controlling the port from said chamber into the expansion chamber whereby the operation of said plunger will positively eject condensate from the condenser side to the expansion side of the system.

6. In a refrigerating apparatus the combination with a compressor pump and compression and expansion chambers adjacent thereto, of means for mechanically ejecting condensate from the pressure side of the system into the expansion side thereof, said means preventing escape of gas therethrough from the expansion side.

7. In a refrigerating system, the combination with expansion and compression chambers, of automatically operating means associated with the pressure side of said system for positively ejecting condensate accumulated in the pressure side of the system to the expansion side thereof.

8. In a refrigerating system, the combination with expansion and compression chambers, of a valve arranged within the pressure side of the system, and an ejector plunger acting upon the condensate accumulated in the pressure side of the system to open said valve and discharge the condensate into the expansion chamber.

9. In a refrigerating system, the combination with expansion and compression chambers, of means normally closing communication between the pressure side of the system and expansion side thereof including a valve, said valve being urged to its seat by a force

- greater than the maximum normal pressure attainable in the pressure side of the system.
10. In a refrigerating system having communicating high and low pressure circuits, a valve closing communication between said circuits and normally urged to open position by the pressure in the high pressure side, and means counteracting the pressure tending to open the valve with a pressure substantially greater than the maximum normal pressure attainable in the high pressure side of the system so that opening of the valve by the pressure in the high pressure side will be prevented.
15. 11. In a refrigerating system having communicating high and low pressure circuits, a valve closing communication between the said circuits and normally urged to open position by the pressure in the high pressure side of the system, means operable to exert a substantially greater pressure than the maximum static pressure attainable in the high pressure side for holding said valve against its seat, and means operable upon an accumulation of condensate in the high pressure side of the system to positively open said valve and discharge the condensate into the low pressure side of the system.
20. 12. In a refrigerating system, the combination with expansion and compression chambers, of means establishing communication between said chambers including a valve arranged in the compression chamber and an ejector plunger reciprocably mounted within the compression chamber and operable only upon an accumulation of condensate in the latter chamber to open said valve and eject the condensate into the expansion chamber aforesaid.
25. 13. In a refrigerating system, the combination with expansion and compression chambers, of a third chamber communicating with the latter chamber for receiving the condensate therefrom and also communicating with the expansion chamber, a spring closed valve for controlling communication between the expansion chamber and third chamber aforesaid, and a plunger disposed in alignment with said third chamber and operable to displace condensate in the latter chamber against the pressure of said spring closed valve.
30. 14. In a refrigerating system, the combination with expansion and compression chambers, of means establishing communication between said chambers including a passage arranged to receive condensate from the compression chamber, a check valve arranged in said passage normally closing the same, means for ejecting condensate in the passage past the valve and into the expansion chamber, said means being incapable of ejecting all of the condensate contained in the passage whereby the latter functions as a liquid seal to prevent the passage of gas from the com-
- pression chamber to the expansion chamber.
35. 15. In a refrigerating system having communicating high and low pressure circuits, means controlling communication between said circuits including a valve member normally urged to open position by the pressure in the high side of the system, means preventing opening of said valve by the maximum normal pressure in the high side of the system, and means for actuating said valve operable only upon an accumulation of condensate above the valve for opening the same.
40. In testimony whereof I affix my signature.
